UNITED STATES PATENT OFFICE.

ABE WILK, OF TOLEDO, OHIO, ASSIGNOR, BY MESNE ASSIGNMENTS, TO THE WILLYS-
OVERLAND COMPANY, OF TOLEDO, OHIO, A CORPORATION OF OHIO.

SPRING SEAT.

1,427,183.

Specification of Letters Patent. Patented Aug. 29, 1922.

Application filed April 13, 1918. Serial No. 228,351.

To all whom it may concern:

Be it known that I, ABE WILK, a citizen of the United States, residing at Toledo, in the county of Lucas and State of Ohio, have invented certain new and useful Improvements in Spring Seats, of which I declare the following to be a full, clear, and exact description.

My invention relates to improvements in spring structures for use in upholstering of vehicle and other seats and cushions, mattresses and the like.

The principal object of the invention is to produce a spring supporting structure which is complete in itself, very easily assembled and eliminates noise caused by the contact of the adjacent springs.

Another object of my invention is to simplify and cheapen the construction of the spring structure without decreasing the efficiency or durability of the same.

Further objects, and objects relating to economies of manufacture and details of construction, will definitely appear from the detailed description to follow:

I accomplish the objects of my invention by the devices and means described in the following specification. My invention is clearly defined and pointed out in the appended claims.

A structure constituting a preferred embodiment of my invention is illustrated in the accompanying drawings, forming a part of this specification, in which:

Fig. I is a top plan view of a spring structure constructed in accordance with my invention, with part of the top layer of the fabric shown broken away.

Figure II is a horizontal, sectional view through the spring structure, being taken substantially on line II-II of Fig. III.

Fig. III is a detail, vertical, section taken substantially on the line III-III of Fig. I.

Fig. IV is a detail, vertical section taken substantially on the line IV-IV of Fig. I.

In general, my invention comprises an improved fabric top and bottom covering, in which the springs are easily mounted to physically retain the springs in uniform and spaced positions, to produce a universally yielding structure and prevent noise due to the contact of the adjacent springs.

The top and bottom coverings each comprises a layer of fabric on the outside, a wire margin frame around which the bor-

der of the covering is secured, preferably by lines of stitching and spaced parallel strips of fabric secured to the inside of the outside layer of fabric to form receptacles for receiving and retaining the terminal 60 rings or convolutions of the springs. There is preferably a strip for each parallel row of springs, which are preferably of the hour-glass type, and the strips are fastened, preferably by lines of stitching, to the outer 65 layer of the fabric. The parallel lines of stitching are preferably at right angles to the length of the strips and equally spaced apart, the terminal convolutions of the springs being positioned in the receptacles 70 between the lines of stitching to properly maintain them in position longitudinally of the strips. The longitudinal edges of the strips are not fastened to the outside layer of fabric, so that the sides of the receptacles 75 are open and the terminal convolutions of the springs are easily slipped through one of the open sides to assemble the springs on the coverings. Means, preferably cords, extend transversely of the length of the strips 80 and are looped about the wires forming the end convolutions of the springs to properly maintain the springs in uniform positions, transversely of the length of the strips.

In carrying my invention into effect, I 85 provide a top and bottom layer, 10 and 11 respectively, of burlap or other suitable fabric, of suitable width and length for the structure to be made. The borders of the top and bottom covers are lapped around 90 wire marginal frames 12 and secured by lines of stitching 13 (Figs. I and II). On the inside of each layer of fabric 10 and 11, spaced parallel strips 14 of any suitable fabric are secured by parallel lines of stitching 95 15 (Figs. I and II). The parallel lines of stitching 15 are at right angles to the length of the parallel strips 14 and are spaced from each other so that the receptacles formed between the top and bottom layers 10 and 110 11 respectively and the portions of the strips 14, between the parallel lines of stitching, are adapted to receive the end convolutions 17 of springs 18.

The end convolutions 17 are inserted in 105 the open sides of the receptacles as heretofore described, and are thereby held in spaced relation to each other longitudinally of the strips 14. The ends of the strips 14 may be lapped about the marginal wire with 110

the ends of the outside layer 10 or 11 and fastened to the outside layer by the lines of stitching 13 so that the end springs are held out of contact with the marginal wire 12, 5 the end receptacles being formed by the lines of stitching 13 and the first line of stitching 15 from each end.

Cords 19, (Fig. I) consisting of a strong fibre and extending transversely across the 10 strips 14 are looped about the adjacent portions of the end convolutions 17 of the springs 18 as indicated at 19 and the end portions of the loops project through the outer layer of fabric 10 or 11. A cord for 15 each transverse row of springs may be used or a single cord for each covering may be used in which case the ends of each transverse portion of the cord are looped about the border wire 12 and the terminal coils of 20 the end springs. These cords hold the springs 18 in spaced relation transversely the length of the springs.

It is apparent from the above description that when the springs 18 are properly assembled on the top and bottom coverings 10 25 and 11, and the cords 19 are secured, there is then no possibility of metallic contact between the springs, whereby it follows that the structure is practically noiseless when 30 in use and the highest resilient efficiency of the springs can be obtained. In forming the assembled structure the top and bottom coverings are first made and then sewed on the respective marginal wire frames 12. 35 The springs are then applied to the covering by clipping their end convolutions into the receptacles formed in the coverings. Finally the cords 19 are applied to the coverings and springs.

40 I am aware that the particular embodiment of my invention is susceptible of considerable variation without departing from the spirit thereof, and, therefore, I desire to claim my invention broadly, as well as specifically, as indicated by the appended claims.

Having thus described my invention, what I claim as new and desire to secure by Letters Patent, is:

50 1. In a device of the class described, the combination of springs and a fabric covering for said springs, strips of fabric stitched at intervals to said first fabric forming receptacles, closed at their two ends and 55 opened at their sides to receive the end coils of the springs, said coils being inserted through the open sides of the receptacles when the covering is assembled on the springs.

60 2. In a device of the class described, the combination of springs, a covering for said springs comprising a layer of fabric and independent strips of fabric secured to the layer by lines of fastening means extending 65 transversely of the strips to form recepta-

cles open at their two sides, the end coils of the springs being adapted to be inserted into the receptacles through one of the open sides thereof when the covering is assembled on the springs.

70

3. In a device of the class described, the combination of springs, a covering for said springs comprising a layer of fabric and independent strips of fabric secured to the layer by lines of fastening means extending 75 transversely of the strips to form receptacles open at their two sides, the end coils of the springs being adapted to be inserted into the receptacles through one of the open sides thereof when the covering is assembled on the springs, the closed ends of the receptacles serving to maintain the proper relative positions of the springs longitudinally of the strips, and means for maintaining the proper relative positions of the 80 springs transversely of the strips.

4. In a device of the class described, the combination of springs, a covering for said springs comprising a layer of fabric and parallel strips of fabric secured to the layer 90 by lines of fastening means extending transversely of the strips to form receptacles open at their two sides, the end coils of the springs being adapted to be inserted into the receptacles through one of the open sides, the 95 ends of the receptacles serving to maintain the proper relative position of the springs longitudinally of the strips, and cords extending transversely of the strips and between the lines of fastening means for maintaining the proper relative positions of the 100 springs transversely of the strips.

5. In a device of the class described, the combination of springs, a covering for said springs comprising a layer of fabric and 105 parallel and spaced strips of fabric secured to the layer by lines of fastening means extending transversely of the strips to form receptacles open at their two sides, the end coils of the springs being adapted to be inserted into the receptacles through one of their open sides and the strips being narrower than the end coils so that the end coils project from each side of the receptacles, and fastening means connected to the layer 110 of fabric and to the projecting portions of the end coils of the springs for maintaining the proper relative positions of the springs transversely of said strips.

6. In a device of the class described, the 120 combination of springs, a covering for said springs comprising a layer of fabric and parallel and spaced strips of fabric secured to the layer by lines of fastening means extending transversely of the strips to form 125 receptacles open at their two sides, the end coils of the springs being adapted to be inserted into the receptacles through one of their open sides and the strips being narrower than the end coils so that the end 130

5 coils project from each side of the receptacles, and cords extending transversely of the strips fastened to the outer layer of fabric and looped about the projecting portions 5 of the springs to maintain the proper relative positions of the springs transversely of the strips.

7. In a device of the class described, the 10 combination of a border frame, springs, a covering for the springs fastened to the frame about its edges and a plurality of strips sewed to said covering at intervals to form receptacles closed at their two ends for receiving the end coils of the springs and 15 provided with open sides whereby the end coils are inserted through one of the open sides of the receptacles when the covering is assembled on the springs.

8. In a device of the class described, the 20 combination of a border frame, springs, and a covering for said springs connected at its edges to the said border frame and comprising a layer of fabric, parallel strips of fabric secured to the layer by lines of fastening means extending transversely of the strips to form receptacles closed at their ends by said fastening means and opened at their sides, the end coils of the springs being adapted to be inserted through one of the 25 open sides of the receptacles into the latter and means for retaining the ends of the coils in position transversely of the strips.

9. In a device of the class described, the 30 combination of a border frame, springs and a covering for said springs comprising a layer of fabric fastened at its edges to said border frame and parallel strips of fabric connected together with the outer layer of fabric to the border frame and secured to 35 said layer by lines of fastening means extending transversely of the strips to form receptacles closed at their ends by the fastening means and opened at their two sides, the end coils of the springs being adapted to be 40 inserted into the receptacles through one of their open sides, the closed ends of the receptacles serving to maintain the proper rela- 45

tive positions of the springs longitudinally of the strips and cords fastened to the border frame and extending transversely of the strips and between the lines of fastening means and fastened to the end coils of the springs for maintaining the proper relative positions of the springs transversely of the strips.

55

10. In a device of the character described, the combination of a plurality of aligned springs, a sheet of flexible material overlying said springs, a strip of flexible material extending parallel with said sheet, said strip 60 being stitched across at points between said springs to form pockets with said sheet open at the sides, an end coil of each of said springs being insertable in one of said pockets through an open side thereof.

65

11. In a device of the class described, the combination with a sheet of flexible material and a plurality of rows of springs having their end coils disposed entirely upon one side of said sheet, independent spaced imperforate strips of flexible material threaded through said end coils, means comprising rows of stitching connecting said strips to said sheet between said coils forming pockets open at one side for inserting said end coils 75 and a border frame surrounding said springs with which the edges of said sheet are connected.

70

12. In a device of the class described, the combination with a sheet of flexible material 80 and a plurality of rows of springs having their end coils disposed entirely upon one side of said sheet, spaced strips of flexible material threaded through said end coils, transverse stitching connecting said strips to said 85 sheet between said coils to prevent displacement of the coils longitudinally of the strips, cords tying said sheet to said coils to prevent lateral displacement of said coils and a border frame surrounding said springs with 90 which the edges of said sheet are connected.

In testimony whereof, I affix my signature.

ABE WILK.
